(57) CLAIM

I claim the ornamental design for a double-headed drumstick, as shown and described.

DESCRIPTION

FIG. 1 is a front view of a double-headed drumstick showing my new design; the undisclosed opposite rear view being identical to FIG. 1;

FIG. 2 is a left-side elevational view thereof, and the undisclosed right-side elevational view is identical to the left-side elevational view;

FIG. 3 is a top plan view thereof; and,

FIG. 4 is a bottom plan view thereof.

The broken lines represent the portions of the double-headed drumstick, which form no part of the claimed design.
